UNITED STATES PATENT OFFICE.

JOHN H. JUNKINS, OF UPPER SANDUSKY, OHIO.

HAY-STACKER.

SPECIFICATION forming part of Letters Patent No. 449,540, dated March 31, 1891.

Application filed September 8, 1890. Serial No. 364,393. (No model.)

To all whom it may concern:

Be it known that I, JOHN H. JUNKINS, a citizen of the United States, residing at Upper Sandusky, in the county of Wyandotte 5 and State of Ohio, have invented certain new and useful Improvements in Hay-Stackers; and I do hereby declare the following to be a full, clear, and exact description of the invention, such as will enable others skilled in the art to which it appertains to make and use the same.

My invention relates to derrick hay-stackers; and it consists of a stacker having a portable platform to which an upright laterally-adjustable post is centrally secured and upon which said post can be adjusted to a vertical position when the machine rests upon an inclined surface, with respect to the horizon by means of longitudinally-extensible and contractile guys fastened to or near the upper end of said post and to the corners of the platform, and a rising and descending and laterally-swinging derrick secured to said post and riding upon a track-plate thereof, and a fork and suitable operating means, this combination serving for elevating, moving, and dumping the hay; and it also consists in certain constructions and combinations of parts, whereby a speedy, easy, and effectual operation of the hay-stacker is secured, as will be hereinafter described.

The objects of my invention are to provide a hay-stacker which is adapted to be freely moved from one place to another, can be readily accommodated to inclinations of the ground, and operated with slight manual labor. I obtain these objects by the mechanism illustrated in the accompanying drawings, in which—

Figure 1 is a perspective view of my invention. Fig. 2 is an elevation of the same, and Fig. 3 a plan view thereof.

The letter A in the drawings designates a platform; B, an upright derrick-post; C, a derrick; D D' D² D³, guys, and E a hay-fork.

The platform A may be of any suitable construction, but preferably is composed of two side bars a, having curved end portions and united by two end bars a' and two central bars a². The side bars a, by reason of their curved ends, can be used as runners on which to move the hay-stacker over the ground in

opposite directions, and the bars a' a², being sufficiently elevated above the ground, will not interfere with this operation. The central bars a² are provided midway of their length with a central post-supporting block a³, in which a central mortise a⁴ is provided. Into this mortise a rabbeted foot portion b of the post B is inserted, said foot portion being of less diameter than the mortise, and thus fitting the same loosely, so that the post may be inclined either backward or forward or otherwise, with respect to the platform A, to any degree answering the steepest slope upon which the hay-stacker is to be operated, and thereby always keeping the post in a position at about a right angle to the horizon. The top of the post B may be provided with an eye b', to which the ends of three guy-rods D 55 D' D² are attached, and a lower eye b², to which a short guy D³ is attached. These four guys are connected to the ends of the bars a' by means of eyes a⁵, and they are at a suitable altitude provided with turn-buckles d, 60 70 75 or other equivalent means, by which they may be shortened or lengthened.

Above the platform A the derrick-post B is provided with a horizontal derrick-riding track-plate b³, which supports the principal 80 weight of a derrick C, hinged to the upper portion of the post, by means of eyes c c' and long staples b⁴ b⁵, in such a manner as to permit the necessary vertical movement and lateral swinging motion of the derrick, as 85 will be presently described. The foot of the derrick is provided with an anti-friction roller c², which rests on an inclined track b⁶ of the plate b³ while being loaded, and by traveling down its inclination facilitates the swinging 90 forward of the loaded derrick. Diametrically opposite the track b⁶ a wedge-shaped limitation-stop b⁷ is provided, against which the roller c² will abut and gradually run thereon as soon as it escapes from the track b⁶ and the plate b³—that is, in the event of the force applied carrying it beyond the plate b³. From 95 this stop the derrick will fall back upon the plate b³ by its own weight. A rope-block e is provided on the swinging end of the horizontal arm c³ of the derrick, and a rope e' is passed around it, and at e² e³ other similar blocks are provided upon the plate b³ and the frame A in order that the rope may be guided 100

- to a position near the ground, convenient for its attachment to a horse. From the block e the rope e' suspends the hay-fork E by means of a bail e^4 , fastened to the head e^5 of the fork.
- 5 The fork E is provided with prongs e^6 and a handle e^7 , to which a cord e^8 is attached.
- The stacker described can be moved to its several places of use without being taken to pieces, and will be ready for operation on its 10 arrival, unless the ground is inclined and the derrick-post B consequently is found not to be vertical with the horizon. In the latter case the turn-buckles d on the lower side of the platform A are turned so as to lengthen 15 the guys, and those on the higher side turned so as to move the post b into its proper vertical position. The hay to be stacked is taken from a place in front of the track—say that indicated by a *—by the operator inserting 20 the prongs of the fork E into the mass of hay, whereupon the horse (not shown) attached to the rope e' pulls up the fork with its load and keeps it suspended, the operator by means of the cord e^8 holding said fork in a horizontal position, and at the same time following 25 the block e , which is swung by the derrick C around to the stacking-place, (indicated, say, by two **), such swinging action taking place automatically by reason of the tendency of 30 the roller c^2 under the weight of the derrick and load to run down the inclined surface of the track b^6 . When the roller c^2 finally comes to a rest upon the horizontal surface 35 of the plate b^3 , the operator, by slackening the cord e^8 , allows the fork and its load to tilt downward, thereby insuring the sliding off of the hay from the prongs e^6 upon the stack, and thereupon the horse is backed toward the 40 hay-stacker and the hay-fork thereby lowered, and the operation just described is repeated. By having the derrick C to rise and descend on staples $b^4 b^5$ and supporting it on the track-plate b^3 of the fixed post B , and elevating 45 and lowering it on the inclined track b^6 , a very light and easily-operated moving hay-stacker is secured as compared with the cumbersome contrivances wherein the post and united crane-arm are moved together in bearings of the platform.
- 50 What I claim as my invention is—
1. In a hay-stacker, in combination, a movable platform A , which is adjustable from a

horizontal to an inclined position and from an inclined to a horizontal position, a derrick-supporting post B , loosely connected at its 55 lower end to said platform, an elevating derrick, and means for connecting the platform and post, whereby the platform may be set inclined to or kept parallel with the horizon and the post always kept at substantially a 60 right angle to the horizon, substantially as described.

2. In a hay-stacker, in combination, a platform A , which is adjustable from a horizontal to an inclined position and from an inclined 65 to a horizontal position, extensible and contractible guys or stays, the derrick-post B , and a derrick, the said guys being connected to the platform and to the post and said post being attached loosely to the platform, so as 70 to allow the platform to be adjusted in the manner stated while it (the post) remains vertical, substantially as described.

3. In a hay-stacker, in combination, a platform which is adjustable from a horizontal to 75 an inclined position and from an inclined to a horizontal position, a derrick-post, a derrick-supporting track-plate having an inclined track, a derrick, a friction-roller, vertically-accommodating hinge connections between 80 the derrick and post, suitable rope-blocks, and a fork, substantially as described.

4. In a hay-stacker, in combination, an adjustable platform A , a derrick-supporting post B , loosely connected to the platform, adjusting and connecting means between the 85 platform and post, a derrick, a derrick-supporting track-plate, and suitable ropes, blocks, and a device for handling the hay, substantially as described. 90

5. In a hay-stacker, in combination, a platform A , a post B , track-plate having inclined track, a derrick, a friction-roller, a vertically-accommodating hinge connection between the derrick and post, suitable means 95 for connecting the post and platform, operating-rope, blocks, and a device for handling the substance to be elevated.

In testimony whereof I hereunto affix my signature in presence of two witnesses.

JOHN H. JUNKINS.
